LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

PERCUSSIVE TOOL.

1,411,253.

Specification of Letters Patent.

Patented Apr. 4, 1922.

Application filed April 6, 1920. Serial No. 371,594.

To all whom it may concern:

Be it known that I, LEWIS C. BAYLES, a citizen of the United States, residing at Easton, in the county of Northampton and 5 State of Pennsylvania, have invented a certain new and useful Improvement in Percussive Tools, of which the following is a specification.

This invention relates to percussive tools 10 but more particularly to that type of tool in which constant fluid pressure is supplied to one forwardly driving face of a differential reciprocating piston constituting the hammer, the distribution of motive fluid to the 15 other faces of the piston being suitably controlled and the exhaust being controlled at least in part by a suitable pressure actuated valve.

In a tool of this type it is desirable to 20 always permit the piston to finish its full stroke before admitting air to reverse it, and furthermore avoid a condition in which air is lost and wasted by flowing through the tool in case the valve sticks or acts sluggish- 25 gishly.

The primary objects of the present invention are to retard the admission to the front end of the cylinder until the piston has finished its stroke, and also to prevent air flowing through the tool due to the valve sticking or acting sluggishly, so that no air can be admitted to either end of the cylinder 30 until the valve has moved and closed the exhaust to that end of the cylinder. This 35 prevents air from entering the cylinder and escaping through the exhaust before the exhaust is closed.

The invention is shown in one of its preferred forms in the accompanying drawings, 40 in which—

Figure 1 is a diagrammatic longitudinal sectional view of so much of a percussive tool as will serve to illustrate the invention with the piston at the beginning of its forward stroke, and

Figure 2 is a similar view showing the piston having finished its forward stroke and about to return on its rearward stroke.

Referring to the drawings, A represents 50 diagrammatically a cylinder of a percussive tool having a main forward bore B and a rearward bore C of smaller diameter. A portion of the shank of the drill steel is indicated at D. A differential piston recipro- 55 ciprocates in the cylinder and is provided

with the main head E fitting the main bore B and a shank or extension preferably formed with an intermediate reduced neck F connecting the portions G and H of the shank of full diameter fitting the smaller bore C.

Fluid pressure is admitted to the cylinder at the inlet J and passes to the smaller bore through the port K so that fluid pressure is constantly maintained on the rearward end 65 face L of the reduced piston shank.

Suitable ports and passages are provided, controlled by the portion H of piston shank for distributing motive fluid to the forward and rearward ends of the main bore B, and 70 exhaust ports T and U adapted to communicate with the port S leading to atmosphere are provided for the main bore controlled by a fluid actuated valve mechanism shown in this instance as a valve P operating in the 75 valve chest Q and actuated by fluid pressure.

The valve mechanism exemplified by the valve P not only controls the exhaust means for the main bore B but includes means for retarding the admission of fluid to the ends 80 of the main bore B until the valve has moved and closed the exhaust at that end of the cylinder. The valve mechanism P also prevents the admission of fluid to either end of the main bore B until the piston has practically finished its stroke, and the valve is thrown.

In order to secure means for carrying out the above described features of my invention, an admission passage V is provided 90 from the inlet J to the port W in the smaller bore C, and another passage X leads from the port Y in the smaller bore C to a port Z at the rear end of the valve chest Q so that motive fluid for actuating the valve P 95 is admitted to the valve chest and the rear end face a of the valve is subjected to fluid pressure. An admission passage b leads from a port c in the smaller bore C to a port d at the forward end of the valve chest 100 Q so that the forward end face e of the valve P is also subjected to motive fluid pressure for actuating the valve.

In accordance with this construction, when the piston is in the position as shown 105 in Figure 1, and about to start on its forward stroke, the valve is thrown to its forward position and motive fluid entering the inlet J passes through the passage V, past the reduced neck F of the piston shank, 110

through the passage X and through the port U to the rear end of the main bore B behind the piston head E for the forward stroke. Fluid pressure in front of the main head E 5 exhausts through the ports T and S during the entire stroke. The valve P owing to the relationship of the ports and passages, is prevented from being thrown until the piston has practically finished its stroke thereby retarding admission of motive fluid to the front end of the main bore B. This is due to the fact that, as shown in Figure 1, 10 no pressure is exerted on the forward face e of the valve until after the rear face L of the piston has advanced and uncovered the port e, by which time the piston will be traveling at a high velocity and will nearly have reached the end of its stroke and the pressure of motive fluid being exerted on 15 the end of the valve P must first overcome the inertia of the same and move the valve before fluid can enter the forward end of the cylinder bore B by which time the piston 20 will have completed its forward stroke.

25 When the valve moves to the position indicated in Figure 2, motive fluid is admitted to the front end of the main bore B and the piston returns on its rearward stroke and the cycle is repeated at the other end. By 30 maintaining motive fluid pressure on the end faces of the valve P for a sufficient time during the piston stroke, I am enabled to accomplish the objects of my invention, and it will be further seen that in case the valve 35 sticks or acts sluggishly loss of fluid pressure through the exhaust ports T and U is prevented.

I claim:

40 1. In a fluid operated percussive tool, the combination of a cylinder having a main bore and a bore of smaller diameter, a differential piston having a head and a shank formed with a reduced neck, means for maintaining constant fluid pressure on the rearward end surface of said piston shank, ports and passageways from the bore of smaller diameter controlled by the piston for distributing fluid to the ends of the main bore, exhaust ports for the main bore, and a

50 valve mechanism controlling said exhaust ports, said valve mechanism including means for preventing the admission of fluid to the main bore until the piston has practically finished its stroke in either direction.

2. In a fluid operated percussive tool, the 55 combination of a cylinder having a main bore and a bore of smaller diameter, a differential piston having a head and a shank formed with a reduced neck, ports and passageways from the bore of smaller diameter 60 controlled by the piston for distributing fluid to the ends of the main bore, exhaust ports for the main bore, a valve chest, and a valve controlling said exhaust ports, the said passageways from the bore of smaller 65 diameter for admitting fluid through the valve chest to the ends of the main bore leading to the ends of the valve chest and subjecting the end faces of the valve directly to the motive fluid pressure, whereby 70 admission of fluid to either end of the main bore is prevented until the valve is thrown and the exhaust closed.

3. In a fluid operated percussive tool, the 75 combination of a cylinder having a main forward bore and rearward bore of smaller diameter, a differential piston reciprocating in said cylinder having a main head fitting the main bore, and a shank or extension formed with an intermediate reduced neck 80 connecting full portions of the shank fitting the smaller bore, means for maintaining constant fluid pressure on the rearward end surface of the said piston shank, ports and passageways from the bore of smaller diameter 85 controlled by the said piston shank for distributing motive fluid to the forward and rearward ends of the main bore, exhaust ports for the main bore and a fluid actuated 90 valve for controlling said exhaust ports, said valve also acting to retard the admission of fluid to the front end of the main bore until the valve has moved and closed the exhaust to that end of the cylinder in order to afford 95 time for the piston to finish its stroke.

In testimony whereof, I have hereunto set my hand.

LEWIS C. BAYLES.
